OPERATING DEVICE FOR POPPET VALVES

Filed Aug. 11, 1927

INVENTOR.

E. R. Taylor.

BY
A. Randolph Jr.
ATTORNEY.

UNITED STATES PATENT OFFICE.

ERNEST R. TAYLOR, OF ARKANSAS CITY, KANSAS.

OPERATING DEVICE FOR POPPET VALVES.

Application filed August 11, 1927. Serial No. 212,263.

The invention relates to the valve operating mechanism of internal combustion engines and has for its object the provision of improved means for adjusting the valve, comprising providing the valve stem with a threaded extremity on which is engaged a contact member for the valve tappet that consists of a disk having a circular projection on its under side forming a shoulder to engage and seat one end of the valve spring and a threaded nipple to engage the threaded extremity of the valve stem, the upper side of the disk being provided with a lug or projection arranged axially of the nipple to sustain the thrust of the tappet mechanism.

The invention will be described in detail hereinafter and will be found illustrated in the accompanying drawings, in which

Figure 1 is a side view in elevation of the upper fragment of an engine cylinder and cylinder head showing the valve operating mechanism with the improved contact member in position on the valve stem,

Figure 2 is a transverse sectional view on a plane substantially through the axis of the valve stem, the valve stem being shown in elevation,

Figure 3 is a side view of the contact member, and

Figure 4 is a top plan view of the contact member.

In the drawings similar reference characters are used to indicate corresponding parts throughout the several views.

The improved operating mechanism for poppet valves is shown in Figures 1 and 2 applied to an engine cylinder A having cylinder head B, with inlet or exhaust port C controlled by a valve D having a stem E, said valve being operated by a tappet F actuated by a push rod G. It will be understood that the type of valve operating mechanism used for illustration is not a part of the invention, and that any other type of valve operating mechanism may be substituted therefor, the invention relating to means hereinafter described to sustain the thrust of the valve spring H and the impact of the valve actuating means or tappet F. The contact member comprises a disk 1 having a circular projection 2 on its under side forming a shoulder 3, said projection 2 being adapted to be re-

ceived within one end of the spring H. An internally threaded nipple 4 is provided that is smaller in diameter than the circular projection 2, said nipple being adapted to engage threaded end 5 of the valve stem E, and the disk 1 is provided with a plurality of radial notches 6 to be engaged by a spanner wrench (not shown) to adjust the contact member on the valve stem. As shown, nipple 4 is spaced from the coils of spring H to obviate drag of said spring on the nipple. 7 designates a jamb nut engaging the end of the nipple 4 to limit the screwing action of the nipple 4 onto the stem E. On the upper side of the disk 1 is a lug or projection 8 that is arranged axially of the nipple 4 and is designed to receive the impact of the valve actuating mechanism such as the tappet F in the type of mechanism illustrated in the drawing.

What is claimed is:

1. In a poppet valve, a valve having a stem, the free end of said stem threaded, a contact member including a disk, an internally threaded nipple on said disk engaging the threads on the stem, a circular projection on the disk of less diameter than the disk and surrounding the nipple aforesaid, said projection forming a shoulder to be received within a valve spring and to space it from said nipple, and a lug on the disk axially aligned with the nipple for engagement with an operating member.

2. In a poppet valve, a valve having a stem, the free end of said stem threaded, a contact member including a disk, a circular projection on one side of said disk of less diameter than the disk forming a shoulder adapted to be received within one end of a valve spring, an internally threaded nipple on said projection engaging the threads on the stem, said nipple being smaller in diameter than the circular projection aforesaid and spaced from said valve spring, a lug on the other side of the disk axially aligned with the nipple for engagement with an operating member, and the disk provided with radial notches cutting its periphery for engagement by a spanner wrench to adjust the position of the contact member on the valve stem.

In testimony whereof I affix my signature.
ERNEST R. TAYLOR.
